PERFORATOR DEVICE

Blackwell K. Murchison, deceased, late of Brooklyn, by
Bessie F. Murchison, executrix, Brooklyn, N. Y.

Application January 17, 1955, Serial No. 482,042

2 Claims. (Cl. 164—113)

This application relates to the art of perforating or punching devices and particularly concerns a novel paper tape perforator.

The apparatus embodying the invention is intended to punch holes in a continuous paper tape on successive lines as the paper is drawn automatically through the apparatus. The apparatus is actuated by electrical pulses received from a typewriter adapted for this purpose as disclosed in copending patent application Serial Number 482,361, filed January 17, 1955. The punched tape may be employed to control a type setting machine such as disclosed in copending application Serial Number 482,041, filed January 17, 1955, and now Patent No. 2,830,820. The perforator embodying the present invention has general application wherever it is desired to punch holes in tape according to a prearranged code, so that the punched tape can be used to operate a type-setting machine, automatic typewriter, telegraph or radio transmitter, addressing machine and so on.

It is a principal object of the invention to provide a perforation device having a unique paper feeding and paper punching mechanism.

It is a further object to provide a perforator device which is wholly controlled in its punching of paper tape by electrical pulses.

It is a further object to provide a paper perforator for punching holes in a continuously fed paper sheet or tape, according to a prearranged code.

Other and further objects and advantages of the invention will become apparent from the following description taken together with the drawing wherein:

Fig. 1 is an elevational side view of a single basic paper feeding and punching mechanism usable in the invention.

Fig. 2 is similar to Fig. 1 but illustrates a step in the paper punching operation of the mechanism.

Fig. 3 shows a front view of a portion of the mechanism as taken on lines 3—3 of Fig. 1.

Fig. 4 shows on an enlarged scale a plan view of a portion of the mechanism as taken on lines 4—4 of Fig. 1.

Fig. 5 shows an elevational side view on an enlarged scale of a portion of the mechanism of Fig. 1.

Fig. 6 is a top plan view of the apparatus embodying the invention.

Fig. 7 is a side elevational view of the apparatus.

Fig. 8 is a rear view of the apparatus.

Fig. 9 is a sectional view taken on lines 9—9 of Fig. 8.

Fig. 10 shows on an enlarged scale a front view partly in section of details of the apparatus.

Fig. 11 is a schematic view of an electrical circuit employed in the apparatus.

The basic paper feeding and perforating mechanism of the apparatus is shown in Figs. 1 and 2. A supply roll R of paper P is carried on roller support wheels 21. The paper passes under the idler transfer roller 22 alongside of guide plate 29, then along the drive roller 23 which has sprocket teeth 24 at its ends. These tips engage in the aligned slots 25 and holes 26, disposed near the edges of

2

the paper and shown clearly in Fig. 3. The paper passes from the drive roller 23 over idler transfer roller 27 alongside of guide plate 29 and then down in a slack loop L into the trough 28 of the guide plate. From the trough 5 the paper passes up over bend 30 in the guide plate then down alongside wall 31 into the passage 32 formed between the spaced plates 33, 34. Both plates 33 and 34 are perforated with a plurality of aligned holes 35 through which pass the individual perforator rods 36 to punch 10 the paper. A lower drive roller 37 provided with sprocket teeth 38 pulls the paper down past plates 33, 34. The paper passes around transfer roller 39, then down in a slack loop L' and over transfer roller 40 to the drive roller 50. Roller 50 has sprocket teeth 51 which engage 15 in apertures 25, 26 of the paper. From roller 50, the paper passes over transfer roller 52 and under transfer roller 53 to be wound up in a roll R' on motor driven take-up roller wheels 54.

The perforator rods 36 are supported for straight line 20 movement through apertures in plates 55, 33 and 34. Each rod 36 has a slot 56 in its inner end in which slides the tapered end of lever 57 as shown on an enlarged scale in Fig. 4. The lever 57 is pivoted on its lower end on a shaft 58 which is engaged in slot 59 near the end of the lever. A shaft pin 60 backs up the lever. Lever 57 carries a pin 61 on which is engaged arm 62. Arm 62 is provided with an aperture 63 to permit movement of the arm in a manner to be described. Arm 62 is biased downward by spring 64 attached to plate 65. Another spring 25 66 biases one end of arm 62 upward so that the arm is snugly engaged in aperture 63. The upper end of spring 66 is anchored on lever 57. Another spring 70 is attached 30 between plate 71 and the end of rod 36 and biases the rod inwardly away from the paper in passage 32.

A guide plate 72 serves to control movement of lever 57 and a guide shaft 73 serves as a fulcrum for arm 62. The arm 62 has a laterally extending finger 74 which extends sufficiently to be engaged by the hooked end 75 of lifter arm 76 shown best in Fig. 2. Arm 76 is biased by 40 spring 77 anchored on plate 78. A bent plate 79 guides the movement of arm 76. The upper end of arm 76 is engaged with shaft 81 which passes through the generally triangular lever 80 shown on an enlarged scale in Fig. 5. A spring 85 connects the upper end of arm 76 and lever 80. A slot 86 is provided in the upper portion 45 of lever 80 and serves to engage the lever with pin 87 attached to plunger 88 of an electromagnet or solenoid 89. The solenoid is provided with electrical terminal conductors 90. The solenoid is carried on brackets 91, 92 supported on plate 93. A shaft 94 serves as a fulcrum for lever 80 and is engaged in slot 95 of the lever 80. The shaft 94 is supported in a bracket plate 96 which is supported on plate 97. A continuously rotatable rubber covered drum 98 is disposed to be contacted by the ends 99 55 of arms 62 when they are lifted by arms 76.

Before discussing the mode of operation of the mechanism above described it would be well to note the disposition of the several parts in the apparatus as shown in Figs. 6 to 10. Fig. 6 is a top plan view of the apparatus 60 in which the several parts are shown without any paper threaded therethrough. The apparatus includes a pair of side frame members 100 which carry the roller support wheels 21 at the top thereof. The several rollers insofar as visible in this drawing are numbered to correspond with the numbering of Figs. 1 and 2. It will be noted that for each aperture 35 there is provided a rod 36, lever 57, arms 62, 76, lever 80 and a solenoid 89. Since 52 rods 36 are provided primarily to punch round holes representative of upper and lower case letters of a font of type, the apparatus contains 52 accompanying sets of levers and arms. More or less apertures and sets of perforating members may be provided as desired.

In Fig. 7 is shown the base 125 which joins the side frame members 100. On the base is mounted the motor 101 which drives the drum 98 by means of belt 102. Another motor 103 is provided to drive the rollers 23 and 50 and one wheel 54. A shaft 104 is rotated by shaft 105 of the motor 103 via worm 106 and gear 112 shown in Fig. 6. The shaft 104 carries a worm 107 which drives a spring belt 108 via a gear 109 and pulley 114. The belt drives pulley 110 connected to a wheel 54 via a shaft pin 111 as shown in Fig. 7. Gear 109 is also connected to drive roller 50 via shaft 113. Shaft 104 carries two additional worms 115 and 116. Gear 131 is driven by worm 115, and serves to drive roller 39. Worm 116 drives gear shaft 120 which is connected to drive roller 23. Step switch 135 drives roller 37 in discrete steps each time a pulse is received via conductors 136.

In Figs. 8 and 9 is shown the stacked assembly of solenoids 89, each being disposed to coact with an associated arm 76. Each arm 76 has a length sufficient to extend up to the plunger 88 of the associated solenoid. The single drum 98 activates each lever 57 via an arm 62. The several levers 57 being disposed in parallel array as shown in the drawing to actuate an individual rod 36.

In Fig. 10 is shown on an enlarged scale a portion of the mechanism used to control the paper drive motor 103. The switch contacts 126, 127 are electrically connected to the motor 103. Contact 126 is movable by the pin 124 which has an insulator head 128. Pin 124 is movable by the slider 129 which contacts circular wedge cam member 130 on gear 117. Gear 117 rotates on a shaft 132 supported by frame member 100. The slider 129 moves in a slot in the hub 133 of gear 131. Gear 131 is driven by worm 115 mounted on shaft 104 shown in Fig. 7 so that gear 131 rotates when motor 103 is actuated. Gear 117 is driven by gear 118 which is driven by gear 119. Gear 119 and roller 37 are both driven by step switch 135 shown in Fig. 7. The step switch is connected to conductors 136 and is actuated by pulses received via these conductors each time a hole is punched in paper P to advance the roller 37 and the paper one step.

In operation a roll of paper R is mounted on roller supports 21 and then threaded around the several rollers as shown in Figs. 1 and 2. It will be noted that slack loops L and L' are initially provided. The paper is threaded through to a spool held by the rollers 54. In Figs. 1 and 2 are shown steps in the punching operation. Initially rods 36 are all retracted from the paper in passage 32 as shown in Fig. 1. When an electric pulse is received by a solenoid 89 via conductors 90 from a typewriter or other source, plunger 88 is electromagnetically retracted, pivoting lever 80 on shaft 94 and raising arm 76. Hook 75 in arm 76 will engage finger 74 on arm 62 and lift it until the end 99 of the arm 62 contacts the continuously rotating drum 98. Arm 62 pivots on pin 61 as it is lifted by the drum until as shown in Fig. 2 shaft 73 is contacted when finger 74 will be clear of hook 75. Spring 77 restores arm 76 to its initial lowered position while arm 62 pivots on shaft 73 thrusting arm 57 forward. Arm 57 in moving forward while pivoting on pin 58, thrusts rod 36 forward to punch a hole in the paper. Arm 62 is at once returned to its original position by spring 64 and rod 36 is retracted by spring 70. So rapid is the movement of arms 62 and 57 and rod 36 that they can complete their cycle of movement before the plunger 88 can again be actuated by another pulse. In normal operation each rod may represent a letter in upper or lower case type of a given font. The position of each hole will thus be representative of the particular type character to be set. As the holes are punched the drive rollers advance the paper in discrete steps while the paper is wound up in roll R'. If the roll R' tends to rotate faster than it passes through passage 32 which may occur if the receipt of pulses is slow while the diameter of R' becomes increasingly larger then loop L'

will tend to become smaller, but means are provided for stopping the rotation of roll until the slack in the paper at L' is restored. This is accomplished by the mechanism shown in part in Figs. 7 and 10. Gear 131 is driven by motor 103 via shaft 104 and worm 115 as above mentioned. The gear 131 turns the slider 129 along the face of cam 130. If gear 117 turns too slowly the slider reaches a low point of cam 130 and is moved inwardly in the slot of hub 133, as contact 126 moves pin 124 and pin head 128 inwardly to break the contact with contact 127. Thus the electrical circuit supply to motor 103 is broken and motor 103 stops. Gear 117 continues to turn however as successive pulses are received and holes are punched in the paper. The cam 130 continues to rotate past the stationary slider 129 gradually pushing it outwardly until contact between contacts 126, 127 is restored when motor 103 resumes rotation to wind up the punched paper on the roll. The motor speed is set so that it will cause the paper to be wound up at the fastest speed at which the paper is punched. The slack loop L is provided so that no tension will occur in the paper between rollers 23 and 37.

Although a single embodiment of the invention has been disclosed this has been by way of illustration only. The invention is not to be construed as limited to this embodiment since many changes are possible without departing from the spirit of the invention as defined by the scope of the appended claims.

What is claimed is:

1. A paper perforator including paper drive means and paper punching means, comprising a plurality of electromagnets which are individually energizable upon receipt of successive electrical pulses, a paper drive roller operative to move a paper past the paper punching means, said punching means including a plurality of punch rods longitudinally movable into and out of engagement with said paper, a pair of perforated plates supporting the paper between them for engagement with said punch rods, said rods being movable by coacting arms, a continuously rotating friction drum, links between said arms and said friction drum, bell cranks connected to said electromagnets and actuated thereby, pull rods interconnecting said bell cranks and said links, whereby the bell cranks are actuated to pull the pull rods and to bring the links into engagement with said friction drum, thereby causing the links to actuate the coacting arms and to thrust the punch rods into punching engagement with the paper to effect punching of the paper, a paper take-up roller, a motor driving said take-up roller, and slack loop control means for stopping the motor responsive to the relative positions of the take-up and paper drive rollers.

2. A paper perforator including paper drive means and paper punching means, comprising a plurality of electromagnets which are individually energizable upon receipt of successive electrical pulses, a paper drive roller operative to move a paper past the paper punching means, said punching means including a plurality of punch rods, longitudinally movable into and out of engagement with said paper, a pair of perforated plates supporting the paper between them for engagement with said punch rods, said rods being movable by coacting arms, a continuously rotating friction drum, links between said arms and said friction drum, bell cranks connected to said electromagnets and actuated thereby, pull rods interconnecting said bell cranks and said links, whereby the bell cranks are actuated to pull the pull rods and to bring the links into engagement with said friction drum, thereby causing the links to actuate the coacting arms and to thrust the punch rods into punching engagement with the paper to effect punching of the paper, a paper take-up roller, a motor driving said take-up roller, and slack loop control means for stopping the motor responsive to the relative positions of the take-up and paper drive rollers, said slack loop control means including a pair of gears connected respectively to the paper drive

roller and the take-up roller, a cam carried by one of said gears and a cam following slider carried by the other gear, said slider being effective to open and close an electrical circuit to said motor.
